UNITED STATES PATENT OFFICE.

OSCAR MAUERSBERGER, OF SCHENECTADY, NEW YORK.

SHOE-FASTENER.

No. 918,571.

Specification of Letters Patent.

Patented April 20, 1909.

Application filed May 22, 1908. Serial No. 434,234.

To all whom it may concern:

Be it known that I, OSCAR MAUERSBERGER, a citizen of the United States, residing at Schenectady, county of Schenectady, State of New York, have invented new and useful Improvements in Shoe-Fasteners, of which the following is a specification.

This invention relates to a shoe fastener which accommodates itself to the shape of the foot, and permits the shoe to be readily opened and closed.

In the accompanying drawing: Figure 1 is a perspective view of a shoe provided with my improved fastener; Fig. 2 is a front view of a portion of the fastener; Fig. 3 a side view of a portion of the keeper, and Fig. 4 a perspective view of the clasp.

Along each edge of the opening slit 10 of a shoe extends a resilient rib or keeper 11 composed of an exposed spirally coiled wire. As shown, the two ribs are made in one piece, being formed of a continuous length of wire extending across vamp 12 below slit 10. The ribs are secured to the uppers 13 by being stitched thereto at suitable intervals, as at 14, and will readily accommodate themselves to the shape of the foot. The ribs, constructed as described, are adapted to be engaged by a series of clasps extending across slit 10, and consisting of a resilient band or body 15, to each end of which is secured a hook 16, of a shape to grasp rib 11. Each

hook 16 is provided along its outer edge with a nail-piece 17, by means of which the clasp may be readily manipulated. This nail-piece is formed by bending the body of the hook first outward and then inward slightly above its free end, to here obtain an outwardly extending double flange.

In use, the clasps are sprung over ribs 11 to directly engage the convolutes thereof. In this way slipping of the clasps is prevented, while, owing to the resilient nature of the clasps and ribs, objectionable pressure is avoided.

To open the shoe, the hooks 16 are, by nail-pieces 17, raised off ribs 11, so that the clasps may be removed.

My improved fastener may also be applied to leggings.

I claim:

A shoe fastener, comprising a pair of exposed resilient coiled wire ribs extending along the opening slit of a shoe, and a series of coöperating clasps each composed of a resilient body, a hook at each end of said body, and an outwardly extending doubled flange on the hook, substantially as specified.

Signed by me at Schenectady, N. Y., this 19th day of May, 1908.

OSCAR MAUERSBERGER.
